GRINDER

Harry A. Maurer, Novelty, Ohio, assignor to The Oster Manufacturing Company, Cleveland, Ohio, a corporation of Ohio

Application January 11, 1937, Serial No. 119,976

2 Claims. (Cl. 51—92)

This invention pertains to a grinding machine of universal application within its field and comprising an arrangement of motive power, stand, and wheels all particularly adapted for use therewith, and work-holding means also particularly adapted to use therewith, such work-holding means comprising a number of modifications of detail within the same principle, for holding, for sharpening or dressing all manner of threading or cutting dies or chasers. A method of sharpening or dressing a plurality of chasers to uniform dimensions is also included in the invention, this method being adapted for, but not limited to, performance by my improved machine.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In the accompanying drawings:

Fig. 1 is a side elevation showing a preferred embodiment of my improved grinder;

Fig. 2 is a plan view of the same grinder, but showing a different grinding wheel attached thereto;

Fig. 3 is a plan view of the work-holding chuck showing a grinding wheel in relation thereto;

Fig. 4 is an enlarged diagrammatic vertical section illustrating the action of a grinding wheel on a chaser to produce the correct contour for working clearance;

Figs. 5 to 11 inclusive are plan views showing several various arrangements of the holder for different types of chasers;

Fig. 12 is a face view of the movable jaw of the work-holder, the point of view being the plane 12—12, Fig. 5, looking in the direction of the arrows and omitting the work piece;

Fig. 13 is a face view of the movable jaw of the work-holder, the point of view being the plane 13—13, Fig. 6, looking in the direction of the arrows and omitting the work piece; and

Fig. 14 is a partial vertical section on plane 14—14, Fig. 11.

The machine, in its preferred embodiment, comprises a base 10 and vertical standard 11. The base carries a table 12 slidable toward and away from the standard on ways 13 by means of a screw 14 manually operated by crank 15. An upper table 16 is slidable longitudinally of the

table 12, that is, transversely of the ways 13. On this table 16 the work-holding chuck is mounted, consisting in detail of a foundation plate 20, a turret head 21 and positioning jaws 22, 23 respectively stationary and movable.

The standard 11 is rotatable in a socket 31 of the base 10 for rotation about its own vertical axis, and can be clamped against rotation by set screw 32. A unitary assembly of motor 33 and grinding wheel 34 is raised and lowered on the standard 11 by the crank 35 operating a threaded shaft 36 with which the frame 37 of the assembly is connected through a slot in the standard 11 by the usual arrangement of a traveling nut, not shown, or other suitable mechanism. The set screw 38 clamps the frame 37 against movement on the standard.

To hold the motor to uniform speed at varying loads, and thus safeguard against bursting the wheel when idle a resistance coil is carried immediately upon the motor case, covered by ventilated shield 40. The arrangements for fastening various sizes of grinding wheels, such as 34 or 34A, to the motor spindle are conventional and not shown in detail. The grinding wheel is guarded as at 39. For convenient portability a flexible cord 42 with the usual plug 43 and switch 44 are provided. It is contemplated that the grinder will ordinarily be made in a bench size, and may be moved from place to place, being carried for example on a wheeled work bench or some similar arrangement.

The chuck includes the base plate 20 and top plate 21 vertically pivoted thereto and capable of being fastened by a lock nut 50 in any angular position within its range of motion, as indicated by the index 51. The positioning jaws, both of which are ordinarily flat plates of about or less than the thickness of a chaser, on the order of one-half inch more or less, and horizontally placed, carried on the upper plate, comprises a segmental jaw 22 movable as in Fig. 3 and with clamping means 55 for jaw 22 including a nut and a bolt the head of which travels in an undercut slot 55', and another movable jaw 23 with adjustment transverse to the movement of 22, by slots 56, and clamped by nuts 57. Where the jaw forms are modified, they are designated in the drawings as 23A and 23B.

As shown in Figs. 12 and 13, the inner surface of each of these jaws contains a series of horizontal holes 70 and 71 threaded and piloted for the insertion of pins whereby the work can be set according to critical surfaces and dimensions, although, to avoid complication of the drawings,

only the holes which are in use are shown in Figs. 5 to 11 inclusive.

Further details and modifications of the chuck turret will be best understood by several specific illustrations, which, however, are not limiting. In Figs. 2 and 3 a chaser C is shown having a long wide shank and a scroll-cam recess 15 at the side. In this type of chaser, the forward edge 16 of the recess 15 is the base with reference to which feed of the cutters is regulated. Consequently this is the datum for grinding work, and the cutter C is held thereto by a pin 17 in the appropriate one of the holes 10. The preferred form of pin is screw threaded and piloted, with 15 a projecting head 18, all as shown in Fig. 5, but other forms of pin may be used.

Further setting, if necessary, is by sliding the plate 22 and locking the fastening 55 in the slot 55'. Thereafter, feed across the face of the 20 grinding wheel is accomplished by traversing the slide 16 by hand. Feed against the wheel for throat grinding, Fig. 2, is obtained by the feed screw 14, but feed against the wheel for lip grinding is by the handle 35 and vertical feed screw 25 36, moving the wheel down to the work, as in Fig. 1.

Fig. 5 shows the set-up for a small short-shanked chaser C'. Here the datum surface is 30 the outer end of the chaser, which is established against the head 18 of the pin 17 in the appropriate hole 10 in the plate 22. In Fig. 6 the arrangement is similar to that of Fig. 3 but reversed, with the front edge of the scroll-cam recess 80 of the chaser C' positioned against a 35 screw in one of the holes 11 in the jaw 23.

Fig. 7 shows a set-up for a wide short chaser C³. Here a long pin 81 is used in the proper hole 10. The jaw plate 22 is here shown slightly offset from concentricity with the plate 21, to adjust the chaser C³ position an amount less than the distance between successive holes 10. The opposite chuck plate 23A is modified, having an increased clearance in front and having both adjustment slots 56A in the other rear half. In 45 Fig. 8 the chaser C⁴ is shouldered against a forward corner of the chuck plate 23. In Fig. 9 the edge of the head of a large headed pin 82 bears against the limiting shoulder of the chaser C⁵ while the face of the head affords further lateral support to the inset side of this chaser.

In Fig. 10 the chaser C⁶ is a modification of that shown in Fig. 6, and is positioned for depth by the pin 17 and held laterally by the wide head of pin 82.

In Fig. 11 the chaser C⁷ is longer than the chuck diameter and also is of a type in which the feed scroll engagement is by a side stud 90. Since chasers with such side studs are made in many sizes, the chuck plate 23B is undercut as at 91, Figs. 11 and 14, to permit stud 90 to pass when C⁷ is moved forward of the position shown in Fig. 11. Holes 71A for locating pins, are formed in the inner edge of the plate 23B. Where the chuck is over-long, as in Fig. 11, a 60 rod 92 secured to plate 23B carries a locating stop 93.

The principal grinding operations on thread-cutting chasers are on the lip and on the throat. The former is shown in Fig. 1, where B indicates the lip angle and the latter by Fig. 2 where D indicates the throat angle. It will be observed that the lip angle B is established by inclination of the face of the grinding wheel 34, shown in Figs. 1 and 3, whereas the throat angle D is 70 established by the inclination of the face plane 75

of the chaser teeth with the face of the grinding wheel, in this instance 34A. Various sizes and shapes of grinding wheels may be employed as required.

Since the angle B does not change except by changing the wheel 34, and since the angle D can be fixed by clamping the turret 21 (index 51 may be graduated in terms of this angle), it will be seen that to grind a set of chasers uniformly to any required angle and depth all that is necessary is to set up the grinder and make successive passes or cuts by traversing the carriage 16. In lip grinding, the feed between successive cuts is accomplished by the handle 35 and vertical screw 36, while in throat grinding the feed is by the handle 15 and screw 14, as already mentioned. Consequently, to grind all four chasers of a set uniformly it is only necessary to set up the turret chuck once. It is to be noted that the chuck jaws 22, 23 do not clamp the chaser tightly, but, with 20 the pins, afford a firm locating fit.

After the turret chuck is set up for the chasers, chaser No. 1 of the set is placed in the chuck, and passed once across the wheel by sliding the table 16 by hand. With the other hand the operator maintains a light pressure on the chaser, keeping it positioned in the chuck. After one pass across the face of the grinding wheel he lays it to one side, returns the table to starting position, inserts chaser No. 2 of the same set in 30 the chuck, passes it across the wheel, removes it, and so on, as before, always picking up his chasers in the same order and making only one pass at a time with each chaser of the series, until the requisite amount of grinding has been 35 done. The method of grinding the lip is indicated by Figs. 3 and 1, and throat grinding by Fig. 2.

It will be understood by those skilled in the art that for throat grinding the wheel 34A must 40 be of the same radius as the curvature of the chaser threads. Fig. 4 illustrates the practice in grinding the chaser throat, where the grinding wheel 34A, indicated by a solid circumferential line, is centered at E, and the concave 45 throat curvature exactly fits the wheel circumference, since it is ground in by the wheel. The broken circle P indicates the circumference of a pipe or a rod which the chaser C is intended to thread, this circle being centered at F. It is 50 thus apparent that only the front edge G of the throat (more strictly speaking, the point of each tooth) will contact the pipe. The divergence of circle P from the solid circle below G indicates the clearance between chaser and work in thread 55 cutting.

It will likewise be apparent to those skilled in the art that my improved tool can also be used for dressing the grinding wheels, by inserting a dressing stick into the chuck instead of a 60 chaser, and bringing the stick into proper relation with the wheel. For dressing a cylindrical wheel, the stick will be arranged square to the wheel, that is, with the dressing edge parallel to the axis of rotation. For dressing a conical 65 wheel, the standard 11 carrying the grinding unit will be turned through a horizontal angle, and set by the clamp screw 32, the angle being such that when the grinding unit is lowered to bring the axis of rotation into the horizontal 70 plane of the dressing stick, the stick will meet the wheel edge at the appropriate angle. This angle can be made entirely by turning the standard 11, or partly by turning the standard 11 and partly by turning the chuck turret 21. While 75

the wheel is in rotation the stick is traversed across the face by sliding the carriage 16.

To maintain nearly uniform speed under both working and idle conditions, thus avoiding excessive idling speed with consequent danger of wheel explosion, I provide a resistance coil in the armature circuit of the motor. The preferred motor is a constant speed universal type, of suitable voltage for use on lighting circuits. 0 This resistor, a permanent part of the apparatus, is housed by the shield 40, perforated for ventilation. The action of the resistor in maintaining uniform speed does not impair the efficiency of the motor under load. This constant speed feature is not in itself a part of my invention, since the resistor is provided by the motor manufacturer.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a chaser grinding machine comprising

a wheel and a horizontal traversing table, the combination with said table of a pair of relatively movable plates thereon, said plates including vertical inner edges defining between them the walls of a groove whereof the table forms the bottom, stud recesses on said inner edges and studs adapted for interchangeable reception in any of said recesses, protruding heads on said studs, said edges and said stud heads adapted to establish positioning contact with controlling surfaces of a chaser laid on said table in said groove. 10

2. In a chaser grinding machine comprising a wheel and a horizontal traversing table, the combination with said table of a pair of relatively movable plates thereon, said plates including inner edges defining between them the walls of a groove whereof the table forms the bottom, a chaser-positioning element, and a plurality of positive engaging means between said groove and said chaser-positioning element for holding the latter in said groove, said edges and said chaser-positioning element being adapted to establish positioning contact with controlling surfaces of a chaser laid on said table in said groove. 20 25

HARRY A. MAURER.
